(57) **CLAIM**

The ornamental design for a chock for a paver support as shown and described.

DESCRIPTION

FIG. 1 is a top back perspective of the chock for a paver support of our invention;

FIG. 2 is a top front perspective view thereof;

FIG. 3 is a bottom back perspective view thereof;

FIG. 4 is a bottom front perspective view thereof;

FIG. 5 is a top plan view thereof;

FIG. 6 is a bottom plan thereof;

FIG. 7 is a left side plan view thereof;

FIG. 8 is a right side plan view thereof;

FIG. 9 is a front plan view thereof; and,

FIG. 10 is a back plan view thereof.
